Israel Foster

ISRAEL FOSTER, OF PHILADELPHIA, PENNSYLVANIA.

Design No. 3,220, dated November 3, 1868.

DESIGN FOR A CARPET-PATTERN.

The Schedule referred to in these Letters Patent and making part of the same.

To all whom it may concern:

Be it known that I, ISRAEL FOSTER, of the city and county of Philadelphia, State of Pennsylvania, have invented or produced a new and original Design for a Carpet-Pattern; and I do hereby declare that the accompanying drawing, and the following explanation thereof, form a full, clear, and exact description of the said design.

The figure in the drawing, which represents the design for a carpet, shows the ornamental figures, composed of flowers, stems, and leaves, too clearly to need description.

Irrespective of the colors employed, I claim—
The design for a carpet-pattern, substantially as described, and as represented in and by the accompanying drawing.

In testimony whereof, I have signed my name to this specification, in the presence of two subscribing witnesses.

ISRAEL FOSTER.

Witnesses:

JOHN WHITE,
JOHN PARKER.
